Filed Jan. 28, 1974, Ser. No. 437,178

Term of patent 14 years

Int. Cl. D22—05

U.S. Cl. D22—27

FIG. 1 is a side view of a fishing lure;

FIG. 2 is a top view; and

FIG. 3 is a front view of the lure.

The fishing lure is symmetrical such that the side opposite to that shown in FIG. 1 appears the same as that shown in FIG. 1.

We claim:

The ornamental design for a fishing lure, as shown and described.
